UNITED STATES PATENT OFFICE.

ORVA A. WILLETT, OF WELLINGTON, KANSAS.

ATTACHMENT FOR LANTERNS.

No. 911,533.

Specification of Letters Patent.

Patented Feb. 2, 1908.

Application filed March 21, 1908. Serial No. 422,506.

To all whom it may concern:

Be it known that I, ORVA A. WILLETT, citizen of the United States, residing at Wellington, in the county of Sumner and State 5 of Kansas, have invented certain new and useful Improvements in Attachments for Lanterns, of which the following is a specification.

This invention contemplates certain new 10 and useful improvements in lanterns, and the object of the invention is an improved lantern attachment which is designed to be operated by the user to cause the lantern to emit a colored light when desired, and which 15 is thus particularly adapted for signaling purposes or the like, since the signalman can use the same lantern to display a colored or white light, according as required.

With this and other objects in view, that 20 will more fully appear as the description proceeds, the invention consists in certain constructions and arrangements of the parts that I shall hereinafter fully describe and then point out the novel features thereof in 25 the appended claims.

For a full understanding of the invention and the merits thereof, and to acquire a knowledge of the details of construction, reference is to be had to the following description and accompanying drawing, in which:

Figure 1 is a side elevation with parts in section, of a lantern showing my improved signaling attachment applied thereto; Fig. 2 35 is a detail view in section, showing the shade in raised position; and, Fig. 3 is a similar view in perspective, of the holder and the adjusting rod.

Corresponding and like parts are referred 40 to in the following description, and indicated in all the views of the drawing, by the same reference characters.

This invention is designed to be applied to 45 a lantern A, which may be of any desired construction or design, except that it embodies a preferably colorless chimney B and a crown plate C secured across the upper end thereof, said crown plate being formed with an aperture D extending therethrough.

50 My improved lantern attachment embodies a preferably cylindrical extensible tube that is constructed in telescopic sections, one of said sections 1 being relatively stationary and constructed of any suitable 55 opaque substance. This section 1 is formed at its upper end with an outstanding flange

2, by means of which it is secured to the crown plate C, and extends downwardly therefrom and in registry with the ventilation hood of said crown plate. The other 60 section of this tube is greater in diameter than the section 1, and is about the same length as the latter, said section being arranged to extend around the flame when the tube is extended, and being constructed of a 65 translucent substance, so as to form a shade 3 adapted to intercept the rays of light and modify the same in color. The shade 3 is provided at its upper end with a preferably metallic collar 4, and its lower end rests 70 against an annular holder 5, and fits in a cupped rim 6 formed at the upper edge of the latter, said holder resting against the body portion of the lantern, when the tube is in extended position, and being formed 75 with notches 7 extending therethrough to admit air to the burner.

A spring adjusting rod 8 is secured at its lower end to the holder 5, and extends upwardly therefrom through the aperture D 80 in the crown plate, said rod being formed near its upper end and near its middle with crimps 9 and 9^a respectively. This rod bears against the outer wall of the aperture D, and the crimp 9 at the upper end of the rod is arranged to be pushed downwardly through the aperture D of the crown plate, when the shade is lowered into an operative position, and is adapted to bear against the crown plate to prevent the rod from sliding through 90 the aperture therein, to permit the shade to accidentally return to an inoperative position during the swinging of the lantern. The intermediate crimp 9^a of the rod is arranged to be passed upwardly through the aperture 95 D, when the shade is raised to an inoperative position and the tube telescoped, and is designed to abut against the crown plate, to suspend the shade securely in such raised position.

It will be noted that the upper or relatively stationary section 1 of the tube, will protect the chimney B of the lantern from smoke and heat, when my improved attachment is not in use.

It is to be understood that the adjusting rod 8 may extend through the lower end of the lantern, in case it is more convenient to operate the shade from the bottom.

From the above description, in connection 110 with the accompanying drawing, it will be apparent that I have provided a simple, du-

rable and efficient lantern attachment which may be readily operated to positively control the color of the light emitted from the lantern, which may be applied to all lanterns of the ordinary type, and which may be easily and cheaply manufactured and its parts readily assembled.

Having thus described the invention, what I claim is:

10 1. The combination with a lantern having a chimney and a crown plate, of an extensible tube constructed in telescoping sections, one of said sections being secured to and depending from the crown plate, and the other 15 section forming a shade, when the tube is extended, and a holder in which the lower end of the shade fits and which is arranged to bear against the body portion of the font around the burner, said holder being provided with means for admitting air to the 20 burner, as and for the purpose specified.

2. The combination with a lantern having a chimney and a crown plate, of an extensible tube constructed in telescoping sections, 25 one of said sections being secured to and depending from said crown plate and the other

section forming a shade, when the tube is extended, an annular holder formed at its upper edge with a cupped rim in which the lower end of the shade fits, said holder being 30 formed at its lower edge with a notch extending therethrough, as and for the purpose specified.

3. The combination with a lantern having a chimney and a crown plate, of an extensible tube constructed in telescoping sections, 35 one of said sections being secured to and depending from the crown plate, and the other section forming a shade adapted to intercept the rays of light when the tube is extended, 40 an annular holder formed at its upper edge with a cupped rim in which the lower end of the shade fits, said holder being formed at its lower edge with notches extending therethrough, and means secured to the holder for holding the sections in telescoped position.

In testimony whereof I affix my signature in presence of two witnesses.

ORVA A. WILLETT. [L. S.]
